UNITED STATES PATENT OFFICE

MICHAEL J. DAVIS, OF BROOKLYN, NEW YORK

ATTACHMENT FOR INTERNAL COMBUSTION ENGINES

Application filed August 30, 1928. Serial No. 302,975.

My invention relates to internal combustion engines and contemplates a simple apparatus to increase the operating efficiency of such engines.

5 It is a well known fact that internal combustion engines, especially the type used in automobiles, operate much more efficiently at night than during the day. This is due to the fact that the night air is damper than the air 10 during the day.

It is a particular object of my invention to provide means for supplying moist air to the combustion chamber of an internal combustion engine. By the provision of this 15 means I also secure the advantage of practically eliminating the carbon deposited in the combustion chamber of the engine since such deposits are augmented by lack of moisture in the air.

20 It is a further object of my invention to supply means for flushing the cylinder and valves with oil in conjunction with the above mentioned means to be operated simultaneously therewith or independently thereof.

25 The provision of this flushing means affords a sure method of lubricating the cylinder walls and valve stems from the combustion chamber which eliminates sticky valves etc.

It is a further object of my invention to 30 so arrange the air moistening means and the flushing device that if desired they may be used as a carburetor by substituting fuel oil for flushing oil.

It is a still further object of my invention 35 to arrange the above mentioned means in a simple inexpensive apparatus, the assembling of which requires no mechanical skill, the manipulation of which is fool-proof, the space occupied by which is small and the upper 40 keep of which is practically negligible.

Further objects and advantages of my invention will appear from the annexed detailed description of the drawings in which:

Fig. 1 is a vertical section through the complete device.

Fig. 2 is a horizontal section through the line 2—2 of Fig. 1.

Referring to the drawings in detail, 1 represents a cylinder closed at its lower end by 50 a cap 2 and at its upper end by a cap 3 and

sealed at both ends by a packing 4. Spaced from the cap 2 is a plate 5 having a series of perforations 6. Plate 5 rests firmly against the packing 4. Mounted inside cylinder 1 is a second cylinder 7 held securely in place between the plate 5 and the cap 3 and rendered water-tight with respect to cylinder 1 by packing 9. Mounted on cap 3 is a nozzle 10 having a stop-cock 11 of any desired make. This nozzle 10 is opened at one end to the atmosphere and at the other end to cylinder 1. Passing longitudinally through cylinder 7 and through caps 2 and 3 is a pipe 12 open at its free end to the atmosphere and provided at the same end with a stop-cock 13. At the lower end of pipe 12 between the plate 5 and the cap 2 are a series of perforations 14, the function of which will be hereinafter stated. Pipe 12 carries fastening means at either end whereby it serves to clamp the various parts in assembled position. Passing through plate 3 and extending nearly to the bottom of cylinder 7 is another pipe 15 open at its lower end and connected at its upper end to a pipe 16 which in turn is connected to the manifold of the engine. Pipe 15 also carries a stop-cock 17 at its upper end. Mounted on cap 3 is another nozzle 18 making a direct connection between the atmosphere and cylinder 7 and provided with a stop-cock 19. Between the pipe 16 and cylinder 1 and providing a passage between the two is a pipe 20. Over the mouth of pipe 20 is a fine mesh screen 20'. Nozzles 10 and 18 are both detachably secured to cap 3 by 55 screw threads or any conventional means whereby, when detached, they provide openings 21 through which liquid may be introduced into cylinders 1 and 7. Attached to one side of cylinder 1 either integrally or detachably is a plate 22 having bolt holes 23 for attaching the device to a support adjacent an internal combustion engine.

It is to be noted that the pipe 16 is connected directly with the manifold of the engine in order to avoid passage of the moist air through the carburetor. The reason for this is that the presence of the moist air in the carburetor has a tendency to raise the vaporization point of the fuel oil and also 50 55 60 65 70 75 80 85 90 95 100

has a tendency to condense by reason of which much carburetor trouble is experienced. I avoid such trouble by leading the moist air into the manifold at one or more 5 points, condensation being eliminated by reason of the great suction caused by various pistons.

The whole device is preferably made of aluminium although it may also be made of 10 glass or any other desired material. In the event that the walls are opaque liquid level gauges of the conventional type are attached thereto. The operation of the device is as follows:

15 Cylinder 1 is substantially filled with water and cylinder 7 is substantially filled with oil. Stop-cocks 13 and 11 are opened and cocks 17 and 19 are closed. The engine is started. The vacuum created in the manifold draws 20 air through the nozzle 10 and through pipe 12. The air passes through pipe 12, through the perforations 14 and is drawn upwardly through the perforations 6 and the water in cylinder 1 to the pipe 20 and thence to the 25 engine. If insufficient moisture is being obtained in the air, cocks 11 and 13 can be regulated to obtain more moisture. By this means the moisture in the air always remains constant and provides air at all times of the 30 same quality as night air. This condition renders manipulation of the carburetor to meet varying atmospheric conditions practically unnecessary.

If the oil in cylinder 7 is of a non-inflammable 35 nature or if it has a suitable flash-point a very satisfactory result can be produced by introducing a small charge of this oil with each charge of gas and air going into the cylinder or at stated intervals because its presence 40 thoroughly lubricates the working parts of the engine and practically prevents the deposition of carbon. This manner of working is effected by opening cocks 17 and 19 simultaneously with cocks 13 and 11 whereupon 45 oil passes from cylinder 7 through the pipe 15 into the pipe 16. The cock 17 can be so adjusted from the dashboard in the conventional manner that a charge of oil can be introduced whenever desired.

50 If it is desired to flush out the engine after a long run cocks 11 and 13 are closed and cocks 17 and 19 are opened. The suction of the manifold, preferably running on the self-starter alone, then draws in oil from cylinder 7, flooding the cylinder and valves where it may be left over night or for a number 55 of hours thereby effecting a thorough cleansing and lubrication of the vital parts of the engine.

60 If it be desired to use this device as a carburetor it is simply necessary to substitute fuel oil for the flushing oil in cylinder 7 and connect cylinder 7 to a fuel supply by the well-known gravity system or any other system. As before stated, the cocks may be op-

erated from the dashboard by utilizing the conventional means for adjusting carburetors from the dashboard. When using the device as a carburetor all the cocks are opened or if desired cock 11 may be kept closed.

70 It is apparent from the above detailed description of my device that it supplies much needed element in the internal combustion engine industry. By the use of such device it is possible to materially cut down the supply 75 of fuel needed for a given run of the engine, to substantially eliminate carbon deposits from the vital parts of the engine, and to keep the engine in smooth running order under trying conditions.

80 Having thus set forth the nature and objects of my invention and described a specific embodiment thereof to which embodiment I in no way limit myself, but on the contrary, contemplate the various obvious modifications of the same, what I claim as new and desire to protect by Letters Patent is:—

85 1. An attachment for an internal combustion engine comprising a pair of annularly spaced cylinders, water tight and air tight with respect to each other, an air inlet on each of said cylinders, an air outlet on one of said cylinders, a liquid outlet on the other of said cylinders and a pipe leading to the manifold of the engine connected to said air outlet and said liquid outlet, the cylinder having the air outlet carrying water and the cylinder having the liquid outlet carrying oil.

90 2. An attachment for an internal combustion engine comprising a cylinder, a cap on either end of said cylinder forming a top and bottom thereof, a perforated plate spaced from the bottom cap of said cylinder, a second cylinder annularly spaced from said first cylinder, said second cylinder being carried between said plate and the top cap of said cylinder and an air pipe passing through said second cylinder to the bottom of said first cylinder, said pipe being perforated at a point between the bottoms of the two cylinders, said first mentioned cylinder being adapted to carry water and carrying a pipe connecting its upper end to the manifold of the engine.

95 3. An attachment for an internal combustion engine comprising a cylinder having a cap at either end providing a top and bottom therefor, a plate having a perforated portion spaced from the bottom of said cylinder, a second cylinder annularly spaced from said first mentioned cylinder and resting on the unperforated portion of said plate, a pipe passing longitudinally through both of said cylinders having one end open to the atmosphere and having perforations at a point between the bottoms of said cylinders, a pipe carried by the top cap of said first mentioned cylinder and extending substantially to the bottom of said second mentioned cylinder, said pipe having its lower end open and its 100

upper end connected to a pipe leading to the manifold of the engine and an air outlet on said first mentioned cylinder connected to said manifold pipe, said first mentioned cylinder comprising a water receptacle, the said second mentioned cylinder comprising an oil receptacle.

4. An attachment for an internal combustion engine comprising a pipe adapted to be connected to a manifold, a water receptacle attached to said pipe, means for causing air to pass through said water receptacle into the manifold, and an oil receptacle, the contents of which are independent of the contents of said water receptacle, attached to said pipe whereby oil is caused to pass through said pipe into said manifold by the suction of the manifold.

In testimony whereof I have hereunto set
20 my hand.

MICHAEL J. DAVIS.
